Inventor:
Elihu Thomson,
by Alexander S. Knott,
His Attorney.

UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

ARC INTERRUPTER.

Application filed February 27, 1924. Serial No. 695,589.

My invention relates to means for extinguishing an electric arc, and has for its object the provision of an improved arc-extinguisher or interrupter which is of compact form and capable of enduring severe service.

It is well known that the flow of electricity in an arc is produced through a stream of metallic vapor or charged particles which passes from one electrode to the other under the influence of an electrostatic field existing between the electrodes. These particles bombard the electrodes, thereby tending to maintain the high temperature which facilitates their production and, in order to interrupt the arc, it is necessary to produce a condition tending to reduce vaporization at the electrodes. Any irregularity in the arc path interferes with the passage of charged particles between the electrodes because of the fact that, due to their momentum, these particles tend to move in straight lines. Such irregularity may be produced either by movement of the electrode or of the arc. The arc may be moved by an air blast or a magnetic field so as to bend or lengthen it and prevent some of the particles from completing the path between electrodes. The arc may also be displaced by interposing a non-conductor in its path. In accordance with my invention improved means are provided for utilizing a plurality of these agencies in quenching an arc.

My invention will be better understood from the following description when considered in connection with the accompanying drawing, and its scope will be pointed out in the appended claims.

Referring to the drawing, Fig. 1 shows an embodiment of my invention; and Figs. 2 and 3 show certain details of its construction.

Fig. 1 shows a combined switch and arc extinguisher. The arc extinguisher is preferably constructed throughout of insulating material and comprises members 1 and 2 which together with plates or slabs 3 and 4 form a passageway open at its two ends. Extending through this passageway in a direction approximately parallel to the sides 3 and 4 is a group of plates 5 supported in any suitable manner by the member 1. A like group of plates 6 partially overlapping or interleaved with but spaced from the

plates 5 is supported by the member 2. The plates 5 and 6 are shown as made in the form of a trapezoid, one edge of each plate 5 being embedded in the block 1, and one edge of each plate 6 being embedded in the block 2. The blocks 1 and 2 are held in spaced relationship by means of the sides 3 and 4 which may be attached to the blocks by means of bolts extending into the holes 7. The inner or free edges of the plates 5 extend into the spaces between the plates 6 and the inner edges of the plates 6 extend into the spaces between the plates 5. It will be observed that the interleaving or overlapping of the two sets of plates 5 and 6 is not constant throughout the passageway but varies from one end to the other so that length of the path which must be followed in traversing the distance between the sides 3 and 4 varies through the length of the passageway.

The plates 5 and 6 are preferably made of an insulating material capable of enduring sudden changes in temperature such as fused quartz, for example. Among the other materials available for this purpose may be mentioned very low expansion glasses, materials known as lava in lava insulators, and highly compressed asbestos sheets filled with vitreous material or laid in mica to reduce their porosity.

The members 1 and 2 may be made of any suitable material possessing sufficiently high insulating properties such as cement or concrete, for example.

In order to facilitate an explanation of the manner in which the arc extinguisher operates, I have illustrated it as combined with an electric switch comprising terminals 8 and 9, stationary contacts 10 and 11 and a movable bridging member 12 for interconnecting the contacts 10 and 11. The bridging member 12 is supported by an arm 13 fixed to the shaft 14. Supports 15 and 16, illustrated as fixed to the sides 3 and 4 respectively of the extinguisher, are provided with bearings 17 in which are supported the ends of the shaft 14. A lever 18 is provided for rotating the shaft 14 to move the bridging member 12 into engagement with the contacts 10 and 11. The lever 18 is biased to open position by a spring 19. A member 20 pivoted at point 21 and arranged to cooperate with a pin 22 is provided for locking the switch in its closed position.

It will be readily understood that an arc between the terminals 10 and 11 will pass the edges of the plates 5 and 6 in a transverse direction, and that if it is forced into the 5 passageway of the extinguisher its length will be greatly increased both due to the fact that it is bowed or bent and because it is forced to follow a zigzag path around the inner edges of the plates. The length of this 10 zigzag path of course increases as the arc is forced farther and farther into the passageway. An electromagnet may be used to force the arc into the passageway. In Fig. 1 this is indicated by poles 23 and 24. Strips 15 25 and 26 conductively associated with the stationary contacts 10 and 11 are provided for facilitating the passage of the arc into the extinguisher. The manner in which a magnetic field acts to displace an arc will be 20 readily understood without detailed explanation. While I have shown the magnet as arranged to produce a field in the same general direction as a straight line drawn between the terminals 10 and 11 it will be apparent 25 that this arrangement is not essential to the operation of the extinguisher but that the magnet may be so arranged as to have its pole pieces adjacent the outer surfaces of the members 1 and 2. In this case the general 30 direction of the magnetic field is perpendicular to instead of parallel to a line drawn between the terminals 10 and 11. In either case, with the proper connections of the magnet exciting windings the arc will be 35 forced into the passageway of the extinguisher due to its tendency to surround the magnetic field. Other means such as an air blast, for example, may be utilized to produce the same effect. This is indicated in 40 Fig. 1 by a pipe 27 shown in Fig. 1. If expedient a magnetic field may be utilized in conjunction with an air blast, the air blast being controlled in response to movement of the switch and the exciting windings of the 45 magnet being partially or wholly energized by the current of the arc. While the extinguisher has been shown as having its passageway extending in a horizontal direction, it will be clear that a vertical passageway 50 may be provided and that the heat of the arc may be utilized to facilitate its movement into the passageway.

The number of plates and the length of the 55 passageway will be determined largely by the operating voltage. In any case the arrangement should be such that the arc is extinguished before it has traveled the entire length of the passageway and the insulation of the plates should be high enough to force 60 the arc around their inner edges as it progresses through the passageway and its length along the sides of the sheets become greater and greater.

I have explained my invention as applied to a switch but it will be readily understood by those skilled in the art that it may be used in connection with many other types of apparatus in which an electric arc is likely to be produced. The terms of the appended claims are, therefore, not restricted to the 65 precise combination shown but are intended to cover all changes and modifications within the spirit and scope of my invention.

What I claim as new and desire to secure by Letters Patent of the United States, is:— 70

1. A device of the class described comprising means forming a passageway, and a plurality of longitudinal insulating plates spaced from one another laterally of said passageway and extending into the same 80 from opposite sides thereof, the arrangement being such that the distance by which said oppositely extending plates overlap varies from one point to another along said passageway.

2. A device of the class described comprising means forming a passageway, a plurality of longitudinal insulating plates spaced from one another laterally of said passageway and extending into the same from opposite sides 90 thereof, and means whereby an electric arc established adjacent one end of and transversely to said plates may be forced into said passageway, the inner edges of said oppositely extending plates being arranged to increase the length of said arc as it travels along said passageway.

3. A device of the class described comprising means forming a passageway, a plurality of longitudinal fused quartz plates spaced from one another laterally of said passageway and extending into the same from opposite sides thereof, and means whereby an electric arc established adjacent one end of and transversely to said plates may be forced into said passageway, said oppositely extending plates being overlapped at their inner edges by a distance which increases from 100 one end of said passageway to the other.

4. A device of the class described comprising means forming a passageway, a plurality of longitudinal insulating plates spaced from one another laterally of said passageway and extending into the same from opposite sides thereof, and means for producing a magnetic field whereby an electric arc established adjacent one end of and transversely to said plates may be forced into said passageway, the inner edges of said oppositely extending plates being arranged to increase the length 110 of said arc as it travels along said passageway.

In witness whereof, I have hereunto set my hand this 23rd day of February, 1924.

ELIHU THOMSON.
